UNITED STATES PATENT OFFICE.

WILLIAM M. DUCKER, OF NEW YORK, N. Y., ASSIGNOR TO DUCKER SECTIONAL BUILDING CORP., OF NEW YORK, N. Y., A CORPORATION OF NEW YORK.

RETAINING DEVICE FOR WINDOW-SASH.

1,384,556.

Specification of Letters Patent. Patented July 12, 1921.

Application filed August 7, 1916. Serial No. 113,622.

To all whom it may concern:

Be it known that I, WILLIAM M. DUCKER, residing at New York, in the county and State of New York, have invented certain 5 new and useful Improvements in Retaining Devices for Window-Sash, of which the following is a specification.

This invention relates to a retaining device for window sash and the object thereof 10 is to provide a simple, efficient device which will serve to maintain the window sash in any adjusted elevated position, without the use of weights or other counterbalancing devices.

15 A further object is to so arrange and construct the parts of the device that they may be manufactured and assembled at small cost, and so that the completed device may be correctly attached to a window sash by 20 a minimum of labor and care.

Other objects and aims of the invention, more or less specific than those referred to above, will be in part obvious and in part 25 pointed out in the course of the following description of the elements, combinations, arrangements of parts and applications of principles, constituting the invention; and the scope of protection contemplated will be indicated in the appended claims.

30 In the accompanying drawings which are to be taken as a part of this specification, and in which I have shown a merely preferred form of embodiment of the invention:

Figure 1 is an elevational view of a window illustrating this invention applied to the sash thereof.

Fig. 2 is an enlarged view of a part of the sash broken away to disclose the manner in which the supporting device is attached 40 thereto.

Fig. 3 is a front elevational view of the supporting device detached.

Fig. 4 is a transverse sectional view taken upon the plane of line IV—IV of Fig. 3.

45 Fig. 5 is a fragmentary perspective view illustrating a portion of the device shown in Figs. 3 and 4.

Fig. 6 is a fragmentary top plan view illustrating the manner of connecting certain 50 portions of the device together; and

Fig. 7 is a transverse sectional view taken upon the plane of line VII—VII of Fig. 6.

Referring to the drawings for a detailed description of the structure shown therein,

the reference character L indicates the window frame and G the sash thereof. The supporting device is indicated generally by the reference character H. In Fig. 1 two sash are illustrated and each of these is provided with two of the supporting devices, one at 55 each side thereof. Since all of the supporting devices are identical in construction and arrangement, one only will be described in detail. It will be understood also that one supporting device may be employed upon 60 each sash, if desired, instead of the two illustrated. In fact, a single supporting device is all that is necessary for small windows.

The supporting device comprises essentially a base member 1, a friction roller 2, a 70 spring 3 resiliently connecting the roller with the base member, and a pawl 4 arranged to prevent rotation of the roller in one direction.

The base member is preferably formed of 75 angle shape, as shown in Fig. 2, having a vertical leg 5 arranged to engage the edge surface of the window frame, and a horizontal leg 6, at the lower end of the vertical leg, projecting into a recess 7 formed in the 80 window sash. A screw 8 may be employed to connect the vertical leg with the material of the sash.

The spring 3 is a double coil spring, that is, it is made up of a single length of wire 85 bent upon itself to form two legs, as clearly shown in Fig. 6. Each of these legs is bent to form a separate coil, as indicated by the reference numerals 9 and 10 in Fig. 3. The coils are spaced somewhat from the point 90 where the legs are connected to each other so as to comprise a straight portion 11. This end portion 11 is disposed to lie flat against the under surface of the leg 6 of the base member and may be fixed thereto in any 95 suitable manner.

Preferably the manner of fixing the portion 11 to the leg 6 of the base member includes a depressed section 12 of the material of the leg 6 so as to form a recess or pocket 100 13 into which the portion 11 extends. After the end of the portion 11 has been inserted within the recess 13 the material of the section 12 is pressed upwardly between the spaced legs of the portion 11 so as to divide 105 the recess 13 into two independent holding pockets. By this means a firm and efficient grip is provided for retaining the spring

fixed to the base member. If desired, the end portion 14 of the leg 6 may be bent down so as to prevent longitudinal movement of the portion 11 in one direction. Longitudinal movement of the portion 11 in the opposite direction is prevented by engagement of the section 12 with rounding walls 15 of the connecting part between the legs of the portion 11, as will be readily understood.

10 The coils 9 and 10 extend laterally from the portion 11 and the outer ends thereof are continued downwardly and are formed with eyes 16 at their lower ends constituting journal bearings for supporting the roller 2, 15 the roller being provided with axle extensions 17 engaging within the eyes 16 for this purpose.

When in use, the roller 2 is held back within the recess 7 of the window sash by 20 engagement with the surface 18 of the window frame L, as shown in Fig. 2. The tension of the spring is continually urging the roller into tight frictional engagement with the surface 18.

25 The roller 2 is provided with a ratchet surface 19 at one side thereof, the teeth of which are arranged to be engaged by a tooth 20 formed as a part of the pawl 4 so as to prevent rotation of the roller in a clock-wise 30 direction.

The pawl 4 is preferably though not necessarily, made from sheet metal and is provided with a relatively large flat body portion 21 apertured as at 22 to receive one of 35 the axle extensions 17 of the roller. The broad flat body portion is intended to lie normally flat against the side of the roller between the toothed portion 19 of said roller and the adjacent end 23 of the coil spring 9.

40 The tooth 20 is formed at the upper end of the body 21, and above said tooth the body is formed with a pair of laterally extending spaced fingers 24 arranged to loosely and slidably and rotatably engage about the leg 23.

45 The aperture 22 is elongated to facilitate the sliding movement of the body longitudinally of the leg 23 to permit the tooth 20 to move upwardly for releasing the teeth of the portion 19 when the window sash is being raised but to permit the tooth to move downwardly into engagement with one of the teeth of the portion 19 when the window sash is being lowered or is in an elevated at 50 rest position.

The space between the surface of the toothed portion 19 and the end 23 of the spring is somewhat greater than the thickness of the body portion 21, and the aperture 22 is sufficiently large, so that the body portion is permitted a limited, or loose swinging movement about an axis substantially parallel to the length of the leg 23 of the spring, as clearly indicated by the dotted 55 lines in Fig. 4 of the drawings.

The rear surfaces of the teeth of the portion 19 preferably have their outer corners beveled off, as at 25, so as to more readily swing the body 21 into the position shown by the dotted lines in Fig. 4 and to thereby 70 more readily free the tooth 20.

The wide part 26 of the body will engage the surface of the portion 19 of the roller to retain the tooth 20 in engaging position at all times.

75 It will thus be seen that the tooth 20 disengages the teeth of the portion 19 by either an upward movement or by a side swinging movement. The object in providing the two means for disengagement is so as to 80 avoid any possibility of a failure of the tooth to disengage itself. Either or both means of disengagement may be brought into play at any time and each is practically independent of the other.

85 It will be understood, of course, that the resilient pressure exerted by the roller against the window frame will retain the sash against possibility of rattling at all times.

90 Having thus described my invention what I claim as new and desire to secure by Letters Patent is:

1. A retaining device for window sash, comprising a spring adapted to be fixed to a window sash, a roller carried directly by said spring, the spring being adapted to urge the roller outwardly from the window sash into frictional engagement with a portion of a window frame, and a separately formed part carried partly by the spring and partly by the roller and interengaging between the roller and a portion of said spring for retaining the roller against rotary movement in one direction.

105 2. A retaining device for window sash, comprising a spring adapted to be fixed to the window sash, a roller carried directly by said spring, the spring being adapted to urge the roller outwardly from the window sash into frictional engagement with a portion of a window frame, ratchet teeth formed upon the roller, and a pawl slidably engaging a portion of said roller to be guided thereby and slidably engaging a portion of said spring to be guided thereby adapted to engage said teeth to retain said roller against rotary movement in one direction.

110 3. A retaining device for window sash, comprising a spring adapted to be fixed to the window sash, a roller carried directly by said spring, the spring being adapted to urge the roller outwardly from the window sash into frictional engagement with a portion of a window frame, a pawl slidably and rotatably engaging a portion of said spring, means whereby the sliding movement of the pawl will permit rotary movement of the wheel in one direction while preventing it in another direction, and means whereby 115 120 125 130

the rotary movement of the pawl will also permit rotation of the roller in one direction while preventing rotation of the roller in the other direction.

- 5 4. A retaining device for window sash, comprising a spring adapted to be fixed to the window sash, a roller carried directly by said spring, the spring being adapted to urge the roller outwardly from the window sash into frictional engagement with a portion of a window frame, ratchet teeth formed upon said roller, said teeth being beveled off at their outer rear corners, and means coöoperating with said beveled outer corners 10 for permitting rotation of the roller in one direction while preventing rotation in the opposite direction.

5. A retaining device for window sash, comprising a spring adapted to be fixed to the window sash, a roller carried directly by said spring, the spring being adapted to urge the roller outwardly from the window sash into frictional engagement with a portion of a window frame, the roller having 20 ratchet teeth formed thereon and having axle portions extending from opposite sides thereof to engage portions of said spring, and a pawl carried by one of said axle portions having an engagement with said spring 25 and having means for engaging said ratchet teeth to prevent rotation of the roller in one direction.

6. A retaining device for window sash, comprising a spring adapted to be fixed to the window sash, a roller carried directly by said spring, the spring being adapted to urge the roller outwardly from the window sash into frictional engagement with a portion of a window frame, the roller having 30 ratchet teeth formed thereon and having axle portions extending from opposite sides thereof to engage portions of said spring, and a pawl for engaging said ratchet teeth to prevent rotation of the roller in one direction, said pawl comprising a member 35 slotted to slidably engage over one of said axle members and having slidable engagement with a portion of said spring.

7. A retaining device for window sash, comprising a spring adapted to be fixed to the window sash, a roller carried directly by said spring, the spring being adapted to urge the roller outwardly from the window sash into frictional engagement with a portion of a window frame, the roller having 40 ratchet teeth formed thereon and having axle portions extending from opposite sides thereof to engage portions of said spring, and a pawl for engaging said ratchet teeth to prevent rotation of the roller in one direction, said pawl comprising a member 45 apertured to receive one of said axle portions having rotary engagement with a portion of said spring, and means for limiting 50 the rotary movement of said pawl.

8. A retaining device for window sash, comprising a roller adapted to be carried by a part of a window and to roll along another part of the window when said parts are moved relative to each other, supporting means whereby said roller is rotatably supported, a ratchet carried by said roller, and means carried partly by said roller and partly by said support adapted to engage 70 said ratchet for retaining said roller against rotary movement in one direction.

9. A retaining device for window sash, comprising a roller adapted to be carried by a part of a window for frictionally engaging another part of a window movable 80 relatively to the first part, supporting means whereby said roller is rotatably supported to rotate when said parts of the window are moved with respect to each other, ratchet teeth formed upon the roller, and a pawl 85 engaging the teeth of the ratchet to prevent rotation of the roller in one direction, said pawl having slidable engagement with said support and also having a flat body portion interposed between the roller and the support 90 for the purpose set forth.

10. A retaining device for window sash, comprising a roller adapted to be carried by a part of a window for frictionally engaging another part of a window movable 95 relatively to the first part, supporting means whereby said roller is rotatably supported to rotate when said parts of the window are moved with respect to each other, ratchet teeth formed upon the roller, a pawl for 100 engaging the teeth of the roller, said pawl having rotary engagement with said support and also having a relatively wide flat body portion interposed between the roller 105 and the support for limiting the rotary movement of the pawl, whereby to retain the roller against rotary movement in one direction.

11. A retaining device for window sash, comprising a base member of angle shape providing a vertical leg adapted to be fixed to one edge surface of a window sash and a horizontal leg adapted to project into a recess formed in the window sash, a spring 110 fixed directly to said horizontal leg, a roller carried directly by said spring, and the means for fixing said spring to said horizontal leg comprising a section of the material of the horizontal leg struck down to 115 form a recess into which a portion of said spring is received.

12. A retaining device for window sash, comprising a base member of angle shape providing a vertical leg adapted to be fixed 120 to one edge surface of a window sash and a horizontal leg adapted to project into a recess formed in the window sash, a spring fixed directly to said horizontal leg, a roller carried directly by said spring, the means 130

for fixing said spring to said horizontal leg comprising a section of the material of the horizontal leg struck down to form a recess into which a portion of said spring is received, the portion of the spring extending into said recess having spaced parts, and the downwardly struck portion of the horizontal leg having a portion pressed up-

wardly between said spaced parts to more firmly retain the spring.

In testimony whereof I affix my signature in the presence of two witnesses.

WILLIAM M. DUCKER.
